(57) **CLAIM**

The ornamental design for a front grill for a pedestal fan, as shown.

DESCRIPTION

FIG. 1 is a front elevational view of a front grill for a pedestal fan showing my new design;

FIG. 2 is a left side elevational view thereof, the opposite side being a mirror image of that shown; and,

FIG. 3 is a top plan view thereof.

The broken line showing of environmental structure in FIGS. 1-3 is for illustrative purposes only and forms no part of the claimed design.
